UNITED STATES PATENT OFFICE

CHARLES WM. KELLER, OF SANTA MONICA, CALIFORNIA

NECKTIE HOLDER

Application filed December 2, 1929. Serial No. 411,129.

This invention relates to necktie holders and especially to a type of holder adapted to be attached to a collar button in place in a collar and its band.

5 It is an object of this invention to provide an extremely simple and practical form of tie holder which will be effective to hold a tie in tied form up close to the collar laps.

A further object is to provide a one-piece 10 article having a front loop to receive the tie and having a closed back loop element to receive the collar button head and neck.

The invention consists in certain advancements in this art as set forth in the ensuing 15 disclosure and having, with the above, additional objects and advantages, and whose construction, combination and details of means, and the manner of operation will be made manifest in the ensuing description of 20 the herewith illustrative apparatus; it being understood that modifications, variations and adaptations may be resorted to within the scope, principle and spirit of the invention as it is more directly claimed hereinafter.

25 Figure 1 is a perspective of the device as applied.

Figure 2 is a perspective of the device.

Figure 3 is a top plan and

Figure 4 is a rear elevation of the holder.

30 This tie holder comprises a back-bone part 2 which has a lower button head receiving aperture 3 merging into a narrower neck receiving slot 4. From the medial part of the back bone 2 extends forwardly a band 35 or loop 5 of sufficient size to receive the contiguous parts of a necktie T when tied in a collar C.

It will be seen that when the device is applied to a collar button B, shown in dotted 40 lines that the device will slide down on the neck of the button and that it will be securely arranged in place against accidental dislodgment from the button since if the holder plays on the collar button neck it cannot readily 45 slip off since the apertures 3—4 form a closed slot in the back bone.

The device is substantial, of low cost, attractive appearance and is easily utilized in 50 application and effectively holds the inserted tie parts.

The band or loop 5 lies in a plane perpendicular to the upright back bone which extends above and below the rear part of the band.

What is claimed is:

1. A necktie holder which is adapted to be applied to a collar button in place, and comprises a closed tie receiving band, and a back-bone part at the rear of the band and extending upwardly and downwardly therefrom; said back-bone consisting of a closed loop having an elongated aperture to receive the head and neck of a collar button. 55

2. A necktie holder which is adapted to be applied to a collar button in place, and comprises a closed tie receiving band, and a back-bone part at the rear of the band and extending upwardly and downwardly therefrom; said back-bone consisting of a perpendicular closed loop bisecting one side of the band and 60 bisected by it and having an elongated aperture to receive the head and neck of a collar button; the aperture consisting of a narrow upper slot and a widened lower opening. 65
